UNITED STATES PATENT OFFICE.

MARTIN A. STRAND, OF NEW RICHMOND, WISCONSIN.

AUTOMATIC WOOD SHAPER.

Application filed May 27, 1922. Serial No. 564,203.

To all whom it may concern:

Be it known that I, MARTIN A. STRAND, a citizen of the United States, residing at New Richmond, in the county of St. Croix and State of Wisconsin, have invented certain new and useful Improvements in Automatic Wood Shapers; and I do hereby declare the following to be a full, clear, and exact description of the invention, such as will enable others skilled in the art to which it appertains to make and use the same.

My invention relates particularly to wood planers or shapers and provides an automatic cutter-head-adjusting device especially adapting the planer for cutting, to proper shape, skis, paddles or similar wooden strips that have varying cross-sections, and, generally stated, the invention consists of the novel devices and combinations of devices hereinafter described and defined in the claims.

The accompanying drawings illustrate the invention applied to a wood planer having an endless traveling bed and overlying yielding pressure rollers. The power-driven rotary cutting head is arranged to rise and fall and such movements are automatically imparted thereto by so-called template bars having the proper contour for causing the cutter head to cut the skis, paddles or other wooden articles to the proper thickness as they are being fed through the machine by the traveling bed.

The operation of the machine will be made clear by the description of its use in making skis. The wooden strips from which the skis are made will preferably be roughed out or cut to approximate outline either by a band-saw or by passing the same through the planer equipped with template bars designed for the roughing out operation. For the purposes of this case, we will assume that the skis have first been cut to such approximate form by either one of the above noted operations and will here describe the finishing operation performed in accordance with my invention.

In the accompanying drawings, which illustrate the invention, like characters indicate like parts throughout the several views.

Referring to the drawings:

Fig. 1 is a side elevation showing the complete machine;

Fig. 2 is a somewhat enlarged section taken on the line 2—2 of Fig. 1;

Fig. 3 is a horizontal section taken approximately on the line 3—3 of Fig. 1, some parts being broken away;

Fig. 4 is a vertical section taken longitudinally through a portion of the machine on the line 4—4 of Fig. 3;

Fig. 5 is a perspective showing a table board equipped with the template bars and with means for holding a plurality of skis in position for simultaneous cutting;

Fig. 6 is a fragmentary section taken on the line 6—6 of Fig. 5;

Fig. 7 is a section on the line 7—7 of Fig. 5; and

Fig. 8 is a perspective showing the ski after it has received its finishing cut but before it has been bent.

Of the parts of the planer, the numeral 9 indicates the framework, the numeral 10 the machine bed in the form of an endless slat and chain belt that runs over sprockets 11 and 12 carried, respectively, by shafts 13 and 14. The cutter head 15 is mounted on a floating shaft 16. The numerals 17 and 18 indicate, respectively, the front and rear pressure rollers. Said rollers 17 and 18 and the cutter head shaft 16 are all journaled in the bracket-like upper ends of laterally spaced bearing plates 19 that are arranged to slide in slightly oblique guideways 20 on the sides of the frame 9. The shaft 16 is provided at its opposite ends with pulleys 21 driven by belts 22. The belts 22 run over driving pulleys 23 on an overhead power shaft 24. The power shaft 24 also carries a driving pulley 25, over which runs a driving belt 26. The belt 26 runs over a pulley 27 on a shaft 28 journaled in the frame 9. The shaft 28 is provided with a spur gear 29 that meshes with a spur gear 30 on the sprocket shaft 14, thereby transmitting motion to the endless feed bed 10. The numeral 31 indicates a feed table adapted to deliver the work to the planer and the numeral 32 indicates a receiving table adapted to receive the work from the machine. The parts of the machine so far described are those of a commercially well known wood planer and, so far as the present invention is concerned, may be varied.

However, the arrangement of the driving belts 22 on lines approximately at right angles to the lines of movements of the guide plates 19 is of considerable importance because it provides an arrangement in which

vertical movements of the cutter head, such as produced automatically as hereinafter described, does not appreciably change the tension of said belts.

5 In applying my invention to the above described machine, I place loosely journaled cutter-controlling rolls or wheels 33 on the cutter head shaft 16 immediately adjacent to the ends of the cutter head and these rolls 10 are arranged to run upon template bars 34. The template bars 34 are laterally spaced and secured to the opposite sides of a portable feed table 35 that is adapted to be placed on the endless feed table 10 and to be there- 15 by carried under the cutter head and pressure rolls 17 and 18.

For holding a plurality of skis Y in parallel relation so that they may be simultaneously presented to the cutter head, the feed 20 table 35 is shown as provided with a transverse rear push bar 36 and a transverse front end clamping bar 37. The bar 37 is notched to receive the pointed front ends of the skis and is adapted to be pressed 25 against the same by a wedge block 38 interposed between the same and a slightly oblique abutment 39 in the form of a bar secured on the front portion of the feed table.

30 By reference particularly to Fig. 5, it will be noted that the template bars 34, at their front end portions 34^a, are raised so that, acting on the rolls 33, they will hold the cutter head elevated and entirely out of 35 cutting action. The extreme front ends of the template bar are tapered so that they will readily enter under the rolls 33. The numeral 40 indicates a hood that overlies the cutter head and is connected to a suction 40 tube 41. Here it may be noted that the heads of the vertically movable bearing brackets 19 will engage the top of the frame 9 and prevent the blades of the cutter head from acting upon the slats of the endless 45 feed belt when the feed table 35 and the work held thereby are removed from the planer. Again by reference to Fig. 5, it will be noted that the template bars 34, at the rear of their raised portions 34^a, 50 are very considerably depressed and that they rise slightly toward their longitudinal centers and then taper off toward their rear ends, approximating in outline to that to be given to the skis. Hence, as the feed 55 table and the skis are carried under the cutter head and pressure rolls, the cutter-con-

trolling rolls 33, running on the said template bars, will first lower, then raise and again lower the cutter head, causing the same to cut, that is, to plane off and finish, 60 the upper surfaces of the skis and giving the skis the desired proper thickness. In this way, accurate finishing of the skis to the exact desired form is made a certain and easy matter and enables high grade 65 work to be done very rapidly and at small manufacturing cost. Obviously, in practice, a number of the portable feed tables may be used, so that these feed tables, loaded with the skis, may be presented one after the other 70 and run in a continuous series through the planer.

What I claim is:

1. The combination with a wood planer having an endless traveling feed bed and 75 a vertically movable cutter head, of a portable feed table manually applicable to and removable from said feed bed having means for holding wooden strips thereon, and template bars secured to said portable feed table 80 and operative to raise and lower said cutter head to thereby determine the longitudinal contour of the wooden strips.

2. The combination with a wood planer having an endless traveling feed bed and a 85 vertically movable power-driven cutter head, of a portable feed table manually applicable to and removable from said feed bed having means for holding wooden strips thereon and provided at its sides with parallel template bars with raised portions in front of the wooden strips held on said table, said template bars operating to raise and lower 90 said cutter head to thereby determine the longitudinal contour of said wooden strips. 95

3. The combination with a planer having an endless traveling feed bed and a power-driven rotary cutter head arranged to freely move vertically and provided at its opposite ends with loosely journaled cutter-controlling rolls, of a portable feed table manually applicable to and removable from said feed bed having means for holding wooden strips thereon, and template bars secured to the opposite sides of said feed table and operative directly on said cutter-controlling rolls to automatically raise and lower said cutter and thereby determine the longitudinal contour given to said wooden strips. 100

In testimony whereof I affix my signature.

MARTIN A. STRAND.
